Giovanni Cataldi.

UNITED STATES PATENT OFFICE.

GIOVANNI CATALDI, OF WASHINGTON, DISTRICT OF COLUMBIA.

SAFETY-ENVELOP.

No. 851,117.

Specification of Letters Patent.

Patented April 23, 1907.

Application filed July 9, 1906. Serial No. 325,328.

To all whom it may concern:

Be it known that I, GIOVANNI CATALDI, a subject of the King of Italy, residing at Washington, in the District of Columbia, have invented certain new and useful Improvements in Safety-Envelopes; and I do declare the following to be a full, clear, and exact description of the invention, such as will enable others skilled in the art to which it appertains to make and use the same.

This invention relates to improvements in safety envelopes, and it consists of certain novel features of construction, combination and arrangement of parts hereinafter described and claimed.

The object of the invention is to provide a simple and inexpensive device of this character, which may be securely locked or sealed, so that its contents can only be reached by tearing it open.

The above and other objects, which will appear as the nature of my invention is better understood, are accomplished by means of the construction illustrated in the accompanying drawings, in which,—

Figure 1 is a plan view of the blank from which the improved envelope is made; Fig. 2 is a perspective view of the envelope showing it partially open, ready to receive its contents; Fig. 3 is a central transverse sectional view through the same in the position shown in Fig. 2; Fig. 4 is a similar view, taken in a plane adjacent to one of the ends of the envelope; Fig. 5 is a longitudinal sectional view; Fig. 6 is a central transverse sectional view, showing the envelope locked or sealed; and Fig. 7 is a detail section on an enlarged scale of one of the self-locking fasteners.

The envelope is made from the single blank shown in Fig. 1 of the drawings, and may be composed of any suitable material. The blank comprises a front portion 1, a back portion 2, two flaps 3, which are adapted to form a central partition in the envelope, and a sealing or locking flap 4. The parts 1, 3, 4, are disposed at the sides and ends of the back 2 and are adapted to be folded over upon the same along the dotted lines shown in Fig. 1. The flaps 3 are substantially rectangular in form and of such length as to overlap each other, as shown at 5, when folded over upon the back 2 to form a central partition in the envelope. These flaps are adapted to have their overlapping ends pasted or otherwise united, and at their

bottom edges are formed sealing flaps 6, adapted to be bent along the dotted lines shown in Fig. 1, and to be pasted upon the inner face of the back 2, as seen in Figs. 3 and 4.

The front 1 has at its ends sealing flaps 7, adapted to be bent over upon the dotted lines shown in Fig. 1, and to be sealed upon the outer face of the back 2, as shown in Fig. 5. Along the free longitudinal edge of the front 1 is formed a re-enforcing band 8, which is separated from the front by a slot 9, which extends between points adjacent to the ends of the same, so that the band 8 is only connected to the front 1 by two necks 10. The band 8 is adapted to be folded over upon the inner face of the central partition formed by the flaps 3 and to be pasted thereto after the members 11 of self-locking fasteners have been passed through or secured in the said partition adjacent to its upper free edge. The fastening members 11 are adapted to be engaged by coacting members 12, which are carried by a similar band upon the sealing and locking flap 4, which latter is adapted to be inserted between the outer face of the partition and the inner face of the front 1. The flap 4 is reinforced by a band 13 formed preferably by doubling the flap upon itself, and the fasteners 12 are passed through the portion 13 or secured therein before the latter is pasted upon the inner face of the flap 4. The latter is of slightly less length than the slot 9, so that it may be readily inserted therethrough and between the partition and the front 1. At each end of the flap 4 are formed on the back 2 small tongues 14, which may be folded into the pocket between the back and the partition and pasted thereto if desired.

While any form of self-locking fastening device may be employed, I preferably use one consisting of two members, which when snapped together cannot be opened. A fastener of this character is shown in Figure 7 of the drawings and it consists of the member 11, which has a pointed head 15 adapted to enter between resilient jaws 16 formed or provided in the coacting member 12, its removal therefrom being prevented by the engagement of a shoulder 17 upon said head 15 with the jaws 16, as clearly shown in Fig. 7. Any number of these resilient stud and socket fasteners may be employed, and they may be arranged in any suitable manner upon the two parts to be locked together.

The construction, use and advantages of the invention will be readily understood from the foregoing description, taken in connection with the accompanying drawings. 5 It will be seen that when the blank 1 has been made up into the envelope shown in Fig. 2, as previously described, the envelope may be effectively locked or sealed, after its contents have been placed in the 10 compartment or space between the back 2 and the central partition, by first bending the flap 4 into the space between the partition and the front 1 and snapping the socket members 12 of the fastening device over the 15 stud members 11. When the fasteners are once closed, it will be impossible to remove the contents of the envelope without destroying the latter. To further seal the envelope, the flap 4 may be glued or pasted to the inner 20 face of the front 1 after the fasteners have been closed. If desired, suitable gum or paste may be provided upon either the inner face of the front or said flap to permit of this sealing.

25 Various changes in the form, proportion and the minor details of construction may be

resorted to without departing from the principle or sacrificing any of the advantages of this invention, as defined by the appended claims.

30

Having thus described my invention, what I claim as new, and desire to secure by Letters-Patent, is,—

A safety envelope formed from a single blank and comprising a front, a back, end 35 flaps adapted to be sealed together to form a central partition, a sealed flap upon said partition, a sealing flap on said front, a reinforcing band on said front connected thereto by necks and separated by a slot, said band being adapted to be sealed to said partition, a flap on said back having a reinforcing band 40 and coacting fastening members carried by said back flap and said partition.

40

In testimony whereof I have hereunto set 45 my hand in presence of two subscribing witnesses.

GIOVANNI CATALDI.
